(57) **CLAIM**

I claim the ornamental design for a bicycle box, as shown and described.

DESCRIPTION

FIG. 1 is a top perspective view of a bicycle box showing my new design, in a fully assembled configuration.

FIG. 2 is a left-side elevation view thereof.

FIG. 3 is a right-side elevation view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is a plan view of the first of two blanks comprising the claimed bicycle box design before assembly; and,

FIG. 9 is a plan view of the second of two blanks comprising the claimed bicycle box design before assembly.

The broken lines in the drawings depict features of the bicycle box, including the handle opening shown in FIGS. 1-5, 8, and 9, and bend lines shown in FIGS. 8-9, that form no part of the claimed design.
